DESIGN FOR A FAUCET

Charles W. Bauberger, Malverne, N. Y.

Application December 2, 1946, Serial No. 135,207

Term of patent 14 years

(Cl. D91—3)

To all whom it may concern:

Be it known that I, Charles W. Bauberger, a citizen of the United States of America, residing at Malverne, Nassau County, State of New York, have invented a new, original, and ornamental Design for a Faucet, of which the following is a specification, reference being had to the accompanying drawing, forming part thereof.

Fig. 1 is a front elevational view of a faucet embodying my invention.

Fig. 2 is a plan view of the same.

Fig. 3 is an end elevational view of the same.

Fig. 4 is a cross-sectional view of the outlet member of the faucet, the section being taken on the plane of the line 4—4 of Fig. 1.

Fig. 5 is an end view and section taken on the plane of the line 5—5 of Fig. 1.

The knob shown in dot-dash lines in Figs. 1 and 2 is shown for illustrative purposes only.

I claim:

The ornamental design for a faucet, substantially as shown and described.

CHARLES W. BAUBERGER.
